UNITED STATES PATENT OFFICE.

PAUL J. RAY, OF LAKEWOOD, OHIO.

ELECTRICAL COMPRESSION RESISTANCE UNIT.

1,213,809.

Specification of Letters Patent. Patented Jan. 23, 1917.

Application filed January 10, 1914. Serial No. 811,433.

To all whom it may concern:

Be it known that I, PAUL J. RAY, a citizen of the United States, residing at Lakewood, in the county of Cuyahoga and State of Ohio, have invented a new and useful Electrical Compression Resistance Unit, of which the following is a specification.

The present invention relates to improvements in electrical compression resistance units, the present structure being an improvement upon that shown in my application for a patent filed May 21, 1913, Serial No. 769,112 for electric current controller and another application filed June 21, 1913, Serial No. 775,158 for compression rheostat, one object of the present invention being the provision of a unit of this character which will attain a greater permanence of resistance, a better operating performance considering the various temperatures to which the resistance medium is subjected, a more desirable exactitude of the conditions desired when subjected to frequent operation, and which does not have to be shaken or jarred to restore the initial resistance value after the compression has been released, the latter advantage being due to the inherent resiliency characteristics of the material used in preparing the resistance disk.

A further object of the invention is the provision of an electrical compression resistance unit provided with a simplified heat radiator disposed to give maximum radiating surface and to be contained in a minimum space.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete device constructed as a compression rheostat, the unit being broken away to foreshorten the same. Fig. 2 is an enlarged longitudinal sectional view through the resistance unit and the radiator. Fig. 3 is a section taken on line 3—3 of Fig. 1.

Referring to the drawings, the numeral 1 designates a support which constitutes with

the clamp 2, which is a two membered means, a proper carrying member for the resistance unit, which, as will presently appear, is mounted in the sleeve 3 of insulation disposed within the clamp 2.

A metal tube 4 is lined with a tube 5 of insulating material and mounted within said insulating tube is a plurality of resistance disks 6, the same being so constructed as to have their resistance increased as the compression thereupon is released and have their resistance reduced as the same are compressed more closely together.

In the lower end of the insulating tube and sleeve at the extreme end of the disk is a metal disk 7 carrying the concentric stem 8 which projects through an insulating sleeve 9, several washers of insulating material 10 being disposed within the tube 4 about the sleeve 9 while several washers 11 of insulating material are disposed about the stem exteriorly of the metal tube 4, as clearly illustrated in Fig. 2. The outer end of the stem 8 is threaded to receive the terminal carrying nuts 12 to which is connected the terminal wire or plate 13.

Mounted in the open end of the sleeve 5 is an insulating bushing 14 in which is mounted for sliding movement, the stem 15 carrying the terminal plate 17 and the button 16 of insulation. Upon the inner end of the stem 15 within the tube 5, as at 18, is attached a screw 19 which is connected to and carries the terminal disk 29 which acts as a means for compressing the compression disks 6 between it and the disk 7.

As shown in my co-pending application Serial No. 775,158, a resilient compression transmitting member 21 abuts the button 16 and is operated by the lever cam 22, as therein described to produce the desired compression action upon the compression disks 6, the member 21 being so constructed as to normally hold the disks 6 in proper contact to prevent any air gaps therebetween as particularly expressed in both of the above mentioned applications.

Each conductor disk 6 is preferably made of carbon or any other material that will be of a less resistance to an electric current when compressed, and is subjected to a process which impregnates, coats or fills the surface with a mixture of carborundum or amorphous carborundum which is commercially known as carborundum fire sand, in

6 finely divided (grain or powdered) form, or grains or powder of any other by-product of the process of manufacturing carborundum, combined with silicate of soda. As 10 the resistance is obtained by the imperfect contact between the surfaces of the disks, and as the disks are formed by sawing sectional-wise plates from a cylindrical piece of material, the saw marks in the surface of the disks are quite uniform and in instances where it is necessary to parallel the 15 surfaces of the disks by grinding them, the conditions of the ground surface are more uniform than the sawed surfaces, thus after the disks have been subjected to the process 20 stated herein, the contact resistance is practically uniform throughout the length of the resistance medium. This feature is a decided advantage over other types of compression resistance units, which do not present uniform resistance as in the operation thereof certain parts of the medium reaches a much higher temperature than the other.

25 The amorphous carborundum which is herein referred to is commercially known as carborundum fire sand and is a by-product of the process of manufacturing carborundum which is made by heating in an electrical furnace coke, sand, salt and sawdust. In the process of manufacturing carborundum, the mixture of materials is heated 30 in a large resistance furnace for about 36 hours; after the reaction is completed, there is left a core of graphite and surrounding the core is a layer of crystallized carborundum, about approximately 16 inches thick and outside of this is a shell of amorphous carborundum which contains a percentage 35 of crystallized carborundum; the remaining materials being unchanged and being used for a new charge. The materials other than the graphite, carborundum and the unchanged mechanical mixture in the foregoing 40 process is known as carborundum fire sand or amorphous carborundum, and either the carborundum fire sand or carborundum are used separately or mixed together in preparing the present disk. In nature, carborundum fire sand differs from carborundum in the respect that it is not as hard 45 or as good an abrasive as carborundum, which is probably due to the lower temperature obtained in the part of the charge in which the fire sand is formed as compared to the temperature obtained in the part 50 where carborundum is formed during the process. However, in formation the carborundum fire sand is clearly allied to the carborundum, as carborundum crystals appear throughout the shell of carborundum fire sand.

55 The use of the mixture of carborundum, as above set forth, with silicate of soda in 60 the process results in a resistance medium

which is not affected by a high temperature as 700° Fahr., as has been found the case in other present types of compression resistance units. The disks, as herein set forth retain their high contact resistance while disks prepared by other methods lose their high contact resistance very rapidly.

65 In preparing the resistance disk 6, the process is carried on by hand or by machine, the pieces being sawed preferably from a cylindrical piece of graphite or hard carbon forming disks, the disk for certain conditions being subjected to the above process while for other conditions are surfaced off parallel by grinding. To produce the best surface 70 upon the disks they are rubbed with a mixture of carborundum or carborundum fire sand and silicate of soda which is done in one way by first coating the disks with silicate of soda or water glass, and then placing the 75 grains or powders of the carborundum or carborundum fire sand upon the film and mixing and rubbing the same in contact with the surface of the disk until a desired smooth 80 surface is effected. The excessive mixture 85 is then removed and the disks are permitted to thoroughly dry before being placed in the tube 5. It is therefore evident that the 90 contact surfaces of the various disks may be varied according to the amount of the mixture retained by the surface, the number of 95 times the disks are subjected to the process, and the condition of the surfaces of the 100 disks before being subjected to the process.

105 The use of carborundum or equivalent material is of advantage, since such material is of an abrasive nature, which renders the high resistance contact surfaces more efficient than others for certain uses. The 110 fact that the material is of an abrasive nature, makes possible the resilient characteristics which almost entirely overcome one of the great objections of compression resistance units previously constructed, which frequently have to be jarred or shaken to 115 restore the initial resistance value after the compression has been relieved.

120 In order to provide a cooling or radiating means for the resistance unit of the present device, two disks 23 and 24 which are 115 flanged disks are placed upon and about the tube 4 and have connected there between the corrugated cylinder 25 which is perforated as at 26 to permit of the proper circulation of the air therethrough. It will thus be 125 seen that by positioning the cylindrical corrugated member 25 about the unit, that a proper circulation of air is accorded to properly maintain the unit against over heating, the heat being radiated therefrom 130 through the aperture 26 so that a draft is created to assist in producing the desired cooling action.

What is claimed is:

1. An electrical compression resistance 130

- unit having a plurality of conductor members whose surfaces are coated with carborundum mixed with an adhesive compound. 2. An electrical compression resistance unit having a plurality of conductor disks whose surfaces are coated with carborundum mixed with silicate of soda. 3. An electrical compression resistance unit having a plurality of conductor members whose surfaces are coated with amorphous carborundum mixed with an adhesive compound. 4. An electrical compression resistance unit having a plurality of conductor disks whose surfaces are coated with amorphous carborundum mixed with silicate of soda. 5. An electrical compression resistance unit having a plurality of conductor members whose surfaces are coated with conductive material having abrasive properties, mixed with an adhesive compound.
- In testimony that I claim the foregoing as my own, I have hereto affixed my signature in the presence of two witnesses.

PAUL J. RAY.
